UNITED STATES PATENT OFFICE.

SAM MITZENMACHER, OF CHICAGO, ILLINOIS, ASSIGNOR OF ONE-HALF TO NATHAN KANET, OF CHICAGO, ILLINOIS.

TURNSTILE REGISTERING APPARATUS.

Application filed May 19, 1922. Serial No. 562,259.

To all whom it may concern:

Be it known that I, SAM MITZENMACHER, a citizen of Russia, residing at Chicago, in the county of Cook and State of Illinois, have invented certain new and useful Improvements in Turnstile Registering Apparatus, of which the following is a specification.

My invention relates to turn stile registering apparatus suitable for use in situations where it is desirable to obtain accurate information as to the number of persons passing a certain point, for example, entering a theatre, public conveyance, or the like.

The principal object of the invention is the provision of a new and improved apparatus of the above character that may be constructed and installed at a relatively low cost, which will be reliable in its operation, and which will be inexpensive to maintain in operative condition.

The invention has for a further and more specific object, the novel arrangement, construction and combination of parts and devices hereinafter described and claimed for carrying out the above stated object and such other objects as will appear from the following description of my invention.

The invention is illustrated in certain preferred embodiments in the accompanying drawing, wherein

Fig. 1 is a side view in elevation of a turnstile and registering apparatus constructed in accordance with my invention, parts of the apparatus being shown in section for the purpose of clearness.

Fig. 2 is a plan view, partly in section, of the structure shown in Fig. 1.

Fig. 3 is a view in perspective of an end portion of one of the turn-stile arms.

Fig. 4 is a fragmentary view in elevation of the registering mechanism and its supporting member, and

Fig. 5 is a view similar to Fig. 1 illustrating a modified construction.

Like characters of reference designate corresponding parts in the several figures of the drawing.

Referring first to Figs. 1 to 4 inclusive of the drawing: In these figures I have shown an embodiment of my invention as comprising a turn-stile 10, registering mechanism 11, and a flexible member 12 connected with the registering mechanism and so positioned with relation to the turn-stile that it is en-

gaged intermittently by portions of the turn-stile when the latter is rotated. The turn-stile preferably consists of four radial extending arms 13 connected at their inner ends in any suitable manner and rotatably supported on a fixed post 14. The outer ends of the arms are preferably provided with enlargements 15, each of which, is formed with a cam surface 16. The registering mechanism 11 may be of any suitable or preferred make. For the purpose of convenience in illustrating the operation of my invention, I have shown in the drawing, a type of registering mechanism having an operating lever 17 adapted when forced downward from the full line position of Fig. 4 to the dotted line position, to effect a change of one unit in the registering mechanism. The registering mechanism is preferably supported at the upper end of a pipe 18. The pipe 18 is attached at its lower end to a suitable base member 19, which in turn is secured to the flooring of the building. A flexible member 12, preferably, a wire, extends through the pipe 18 and is attached at one end to the base 19 and at the other end to the lower end of a rod 20, the rod being connected at its upper end to the end of the operating lever 17. The wire 12 is of such length that it is normally taut when the operating lever 17 is in the full line position of Fig. 4. A coiled spring 21 surrounds the rod 20 and is connected at its lower end to the rod and at its upper end to the pipe 18 and is adapted to return the operating lever 17 to its normally full line position and maintain the wire 12 taut. The pipe 18 is formed with an opening 22 in the path of travel of the end portions of the turn-stile arms 13 so that when the arms are rotated, for example, by a person passing through the turn-stile in the direction indicated by the arrow in Fig. 2, the cam surfaces 16 at the outer ends of the turn-stile arms will engage the wire 12 and thereby exert a downward pull on the lever 17.

The coil spring 21 effects the return of the lever 17 and the wires 12 to their normal position as soon as the wire is freed from its engagement with the cam surface 16. In devices of the above character, it is desirable that the arms of the turn-stile be capable of rotating in one direction only. I preferably obtain this result by the provision of a spring tongue 23 adapted to en-

105
110

gage with suitable ratchet teeth 24 formed on the under side of the member connecting the arms 13.

In Fig. 5 I have shown a modified construction, in which the turn-stile arms 13^a are connected rigidly to a vertical shaft 25. The shaft 25 is enclosed in a pipe 26 and extends below the flooring 27 and is supported by a suitable bearing 28. Arms 29, 10 somewhat longer than the arms 13^a are fixed to the shaft 25 at a point below the flooring and are provided at their ends with enlargements 15^a having cam surfaces 16^a which engage with the wire 12^a, the latter of which 15 extends below the floor 27 and is attached by means of an eye-screw 30 to a sub-flooring 31. In other respects, this modification may be constructed substantially as shown in Figs. 1 to 4 inclusive.

20 Having described my invention, what I claim is:

1. In apparatus of the character described, the combination with a turn-stile having radially extending arms adapted to rotate 25 on a vertical axis, of means for registering predetermined movements of said arms comprising registering mechanism, and means for actuating said registering mechanism comprising a normally taut flexible member 30 positioned in the path of travel of said arms so as to be engaged thereby.

2. In apparatus of the character described,

the combination with a turn-stile having radially extending arms adapted to rotate on a vertical axis, of means for registering 35 predetermined movements of said arms, comprising registering mechanism, an oscillating member, a wire attached at one end to a fixed element and at the other end to said oscillating member so as to traverse 40 the path of travel of said arms, and a spring coil member adapted to maintain said wire taut.

3. In apparatus of the character described, the combination with a turn-stile having 45 radially extending arms adapted to rotate on a vertical axis, of means for registering predetermined movements of said arms, comprising a hollow support, registering mechanism attached to the upper end of 50 said support, and means for actuating said registering mechanism comprising a flexible member, extending through said hollow support, connected at one end with said registering mechanism and attached at the 55 other end to a fixed element so as to traverse the path of travel of said rotating arms, and a coiled spring connected to said member and to said support adapted to maintain 60 said flexible member taut; said hollow support being formed with an opening through which the ends of said rotating arms pass into engagement with said flexible member.

SAM MITZENMACHER.
